UNITED STATES PATENT OFFICE.

CHARLES B. WADE, OF ROANOKE, VIRGINIA.

AUTOMATIC SAFETY ATTACHMENT FOR PNEUMATIC HAMMERS.

Application filed March 12, 1923. Serial No. 624,601.

The present invention relates to pneumatic hammers and has for its object to provide a safety device which will prevent the flying off of the bit or tool, when the hammer is lifted from the work without first releasing the valve trigger to stop the action of the fluid upon the plunger.

It often happens that the starting trigger is accidentally pressed, when the hammer is not in use and this causes the tool or bit to fly out causing injuries to bystanders and the main object of the invention is now to provide an attachment for pneumatic hammers that will prevent such accidents. This attachment can be applied to any hammer of this class with only slight alteration thereof, and at very little cost.

It is evident that by this arrangement not only the tool or bit will be prevented from flying out accidentally but also the plunger actuating the bit will be prevented from doing damage whether the bit is in position or not.

In the accompanying drawings one embodiment of the invention is illustrated, and;

Figure 1 represents a side elevation of a pneumatic hammer with the safety attachment installed thereon;

Figure 2 is a partial longitudinal section of the device taken along line 2—2 of Figure 1;

Figure 3 is a transverse section along line 3—3 of Figure 1;

Figure 4 is a partial transverse section along line 4—4 of Figure 1;

Figure 5 is a half longitudinal section and half elevation of a pneumatic hammer equipped with this device which is built into the housing of the hammer;

Figure 6 is a transverse section along line 6—6 of Figure 5; and

Figure 7 is a transverse section along line 7—7 of Figure 5.

Referring first to the device as illustrated in Figures 1 to 4, reference numeral 10 represents the head of the housing of a pneumatic hammer of any modern construction and provided with a handle 11 having a hose connection as at 12 and a valve trigger 13 for admitting the pressure fluid into the passage 14 in the handle. Ordinarily this passage opens directly into the central cavity of the housing to act upon a reciprocating plunger which produces the blows on the tool or bit 15 at the forward or lower end of the housing. As shown in Figure 1, this

bit is held in position by a flexible clip 16 to admit of the limited longitudinal motion of the bit 15, when positioned in the end of the housing. The bit is provided with the usual shoulder 17 projecting radially beyond the shank 18, which holds the bit in position in the housing. The features of the pneumatic hammer described so far are similar in all such tools and form no part of the present invention.

The safety device consists of a substantially cylindrical casing 19 having a chamber 20 which is closed at its upper end by a threaded cap 21. The chamber 20 tapers 70 downwardly to form a seat 22 for a valve 23 normally seated by means of a coil spring 24 surrounding the valve spindle 25. The latter is guided at its upper end in the corresponding recess 26 furnished in the cap 75 21 and in order that the casing 19 may be made as short as possible the upper end of the coil spring 24 is seated in a counterbore 27 furnished in the cap 21.

Below the valve seat 22, the chamber 20 80 is slightly restricted as at 28 and opens into the transverse passage 29. Below this passage a central bearing 30 is formed for the valve-controlling rod 31 and this bearing terminates with a threaded shank 32 over 85 which a packing nut 33 is placed, and between the shank and the nut is furnished a suitable packing 34. In this manner a packing box is furnished for the actuating rod 31.

The lower end of the rod 31 terminates with the socket portion 35, which is threaded internally to engage with the correspondingly threaded extension rod 36 and a lock nut 37 tightens the connection of the two 95 rods. The added length of the rod 31 and the extension rod 36 is such that when the bit 15 is in its lowered position, as seen in Figure 1, and the lower end of the extension rod 36 rests on the shoulder 17, the upper 100 end of the rod 31 is slightly below the valve head 23, so that the seating of the valve is insured by the action of the coil spring 24.

In order to guide the extension rod 36, a sleeve 38 is furnished and preferably secured along the outer surface of the housing 10 by spot welding the inwardly directed wedge-shaped fin 39. It will be evident that in order to position the lower end of the extension rod 36 in proper relation with the 110 shoulder 17 of the bit, the side of the housing has to be grooved or gouged out as at 40.

Ordinarily the passage 14 in the handle 11 communicates directly with the chamber in the housing for directing the fluid pressure against the plunger; this communication takes place through a port 41 furnished in the upper end of the housing. It will now be necessary to drill an aperture 42 across this port 41, as best seen in Figure 3, and to divide this aperture by an inserted 10 plug 43. The end of this aperture 42 nearest to the passage 14 has a port 44 to one side thereof, and between this port and the corresponding port 45 leading into the chamber 20 in the casing 19 is inserted a 15 piece of pipe 46 which is preferably spot welded to the casing as well as to the head of the housing, as best seen in Figure 3. The port 29 at the lower end of the casing 19 is similarly connected by means of a pipe 20 47 with the other end of the aperture 42, and this pipe is also spot welded both to the head 10 and the casing 19. It will thus be evident that when the valve trigger 13 is 25 pressed, fluid will be admitted from the hose 12 through the passage 14 and through the port 44, pipe 46 and port 45 into the upper end of the chamber 20. As the outlet 28 from this chamber is closed by the valve 23 actuated by the coil spring 24, the fluid 30 pressure can proceed no further until the valve is lifted by the pressing of the bit 15 against the work, when the shoulder 17 will 35 press the extension rod 36 and the rod 31 upwards and lift the valve, whereupon the fluid pressure can proceed through the port 29 and the pipe 47 into the aperture 42 and through the port 41 to act upon the plunger in the ordinary manner. It will thus be 40 evident that both the trigger 13 and the valve 23 have to be simultaneously actuated to operate the bit 15.

Referring now to Figures 5 to 7 inclusive, these figures illustrate a pneumatic hammer into which the safety device has been built 45 from the start, so that no attachment therefor is needed. In this case the housing 50 has an eccentric duct as at 51 in which the valve-controlling rod 52 is mounted to reciprocate so that its lower end engages with 50 the shoulder 17 of the bit 15 as previously described. This duct continues upwardly and opens into an annular groove 69 provided in a nut 53, in which the fluid passage 54 is furnished from the handle 55 of the 55 hammer. A cap 56 is threaded into the top of this nut 53 and is provided with a side port 57 connecting with the passage 54.

This port leads into the chamber 58 in the cap, which terminates at the lower end with the valve seat 59 for the valve 60, held in 60 position by means of a coil spring 61. The upper end of the chamber is threaded to receive a plug 62 forming an abutment for the upper end of the coil spring 61 and the chamber 58 communicates downwardly with the eccentric bore or duct 51 which is enlarged, as at 70, to form a port similar to 29 in Fig. 2. From this port the pressure fluid is led through suitable conduits and delivered against the hammer in the usual 70 manner.

The action of the parts is identical with that of the attachable safety device already described and no further description of the use and action of this complete pneumatic 75 hammer is needed.

When in the claim, the term "bit" is used, this is meant to include any kind of punch, rivet set, or tool operated by a pneumatic hammer.

Having thus described the invention what is claimed as new is:

The combination with a housing having a laterally extending inlet passage for pressure fluid in its upper end and having a 85 pressure chamber below and closed to said passage, a tool in the lower end of the housing, and a valve-controlling rod in contact with the tool and extending longitudinally of the housing to a point between the inlet 90 passage and the pressure chamber, of a valve chamber at the upper end of the housing eccentric to the pressure chamber receiving the upper end of said rod and extending longitudinally of the housing across 95 and communicating with the end of said inlet passage, the valve chamber communicating through its lower end with the pressure chamber and having a seat disposed 100 between the said inlet passage and said pressure chamber, the inlet passage and the pressure chamber being out of communication except through the lower end of the valve chamber, a valve in said valve chamber arranged to rest on said valve seat to 105 normally cut-off flow into the pressure chamber and be unseated by impact of the valve-controlling rod, and yieldable means within the valve chamber for holding the valve normally seated.

In testimony whereof I affix my signature.

CHARLES B. WADE. [L.S.]
